ROTARY PUMP

William Ward Davidson, Chicago, Ill.

Application July 31, 1936, Serial No. 93,633

3 Claims. (Cl. 230—139)

This invention relates to improvements in rotary pumps or compressors of all kinds but particularly to those designed and adapted for use as gas compressors in small refrigerating plants such as are now commonly used in house refrigerators.

A principal object of the invention is to provide a rotary compressor or pump, combined with a motor for operating same, which shall be of the most simple construction and which shall combine in one rotatable unit the rotatable part of the compressor and the rotatable part of the motor.

A further object of the invention is to provide a combined compressor and motor in which the overall axial dimension shall be reduced to that required for the compressor.

A further object is to provide a combined compressor and motor arranged in a sealed casing of minimum dimensions and automatic means for continuously oiling the bearings and opposed movable surfaces of the compressor.

The invention includes an electric motor for driving the compressor and having an enlarged rotor within which the compressor is arranged, to be driven thereby, and which construction results in a compressor of minimum height and high efficiency.

The invention also includes the arrangement of the compressor, the rotor of the motor and the stator or field of the motor all in substantially a single plane and preferably in a horizontal plane with the axis of rotation of the compressor arranged vertically.

It should be understood that many of the features of the invention are capable of incorporation in assemblies other than compressors, such for instance vacuum or exhaust pumps and pressure pumps for gases, air or liquids and that in the use of the word compressor it is intended to include all other possible machines other than the preferred embodiment of the invention herein shown and described as a compressor. In other words it should be understood that the invention and its various novel features are not limited merely to compressors for use in refrigerating systems.

To attain the objects and benefits of the invention, a pump or compressor embodying the invention and improvement, comprises the various features, combinations of features and details of construction hereinafter described and claimed.

In the accompanying drawings forming part of this specification, and in which a preferred form of the invention is fully illustrated:

Fig. 1 is a vertical, central section, having parts broken away for more clearly showing the invention and taken on the line 1—1 of Fig. 2;

Fig. 2 is a top plan view of the compressor shown in Fig. 1;

Fig. 3 is a fragmentary, horizontal section on the line 3—3 of Fig. 1;

Fig. 4 is a vertical, central section of the rotating parts of the compressor and taken substantially on the line 4—4 of Fig. 11;

Fig. 5 is a section similar to Fig. 4; but taken on the line 5—5 of Fig. 10;

Fig. 6 is a bottom perspective view of the upper head of the compressor cylinder;

Fig. 7 is a top perspective view of the compressor rotor;

Fig. 8 is a bottom perspective view of the lower cylinder head of the compressor cylinder;

Figs. 9, 10, 11 and 12 are horizontal sections on the lines 9—9, 10—10, 11—11 and 12—12 respectively of Fig. 4;

Fig. 13 is a perspective view of a part of the compressor shaft;

Fig. 14 is a fragmentary section of the lower cylinder head on the line 14—14 of Fig. 12;

Fig. 15 is a fragmentary horizontal section on the line 15—15 of Fig. 1; and

Figs. 16 and 17 are fragmentary vertical sections on the lines 16—16 and 17—17 respectively of Fig. 15.

The complete compressor, shown in the drawings comprises a rotary compressor A, an electric motor B of peculiar construction and a casing or dome C within which the compressor and motor are enclosed. The casing is circular in horizontal cross section, the compressor is arranged on a vertical axis located centrally of the casing and the motor is arranged encircling the compressor and between the compressor and the circular wall of the casing. This arrangement of the compressor and the motor results in many important advantages and results among which are; the possible provision of adequately strong and rigid bearings for the compressor located close to the compression cylinder at each side thereof, thus enabling the elimination of any flexure of parts due to the high pressure and forces involved and also the reduction of over all dimensions to a minimum especially as to height as the compressor and the motor are in effect concentric with each other and only require height sufficient for the compressor.

While the drawings show the compressor as being built with a vertically arranged shaft it should be understood that the invention is not

limited to such construction, it simply means, that at this time it is considered that this form is the preferred form, as it obviously has advantages over a form in which the compressor would be provided with a horizontally disposed shaft.

The compressor A comprises a cylinder 20 arranged on a vertical axis and closed at its upper end by a head 21 having a flat inner surface 22 and secured to the cylinder 20 by bolts 23.

The cylinder is closed at its lower end by a similar head 24 having a like flat inner surface 25 and is secured in place by bolts 26.

The cylinder has a cylindrical concentric bore 27 extending straight through from end to end and which bore is closed at its ends by the heads 21 and 24.

Within the bore 27 is arranged a rotor or rotary piston or core 28, which is of equal length with the cylinder and has flat upper and lower ends 29 and 30 opposed to the flat inner faces 20 of the cylinder heads.

The rotor 28 is mounted on a vertical shaft 31 and is rigidly secured thereon to rotate therewith, by any suitable means, such as a radial set screw 32, see Fig. 4.

The compressor shaft 31 is arranged eccentric to the cylinder 20 and concentric in relation to the rotor 28, as best shown in Fig. 3 and the diameters of the rotor 28 and the cylinder bore 27 are such that the outer cylindrical surface of the rotor is tangential to the cylindrical surface of the bore at one side of the cylinder as shown at 33, Fig. 3, thus providing a crescent shaped space 34 between the rotor and the cylinder and extending from end to end of the cylinder and which constitutes the pumping or compression space of the compressor. The eccentricity is indicated on Figs. 4 and 5 by the two dot and dash center lines shown thereon.

The casing C within which the compressor A and motor B are arranged is made fluid-tight and has a cylindrical side wall 35 closed at its bottom by an integral wall 36 and closed at its top by a removable head 37 secured to a peripheral flange 38 on the wall 35 by bolts 39. A suitable packing 40 is interposed between the flange 38 and head 37 to make the casing pressure-tight. As shown the wall 35 is provided with heat-radiating ribs 41 and the head 37 is provided with similar heat-radiating ribs 42 to assist in dispersing the heat produced when the compressor is operating.

Centrally disposed on the lower head 36 and rising within the casing is a bearing member 43 provided with a central bore 44 in which a bearing sleeve 45 of suitable metal, is fixed.

The lower end 46 of the compressor shaft 31 is mounted for rotation within the bearing sleeve 45. The bearing member 43 is provided with a circular base 47 and the lower head 36 of the casing is provided with a circular depression 48 concentric with the casing wall 35 and in which the base 47 fits and it is rigidly secured in place by bolts 49. A bearing member 50, similar to the bearing member 43 is arranged in the upper part of the casing and is provided with a vertical bore 51 in axial alignment with the bore 44 of the lower bearing member 43 and within (in a bearing sleeve) which the upper end 52 of the compressor shaft is mounted for rotating. This bearing will be described more fully hereinafter. The two bearing members 43 and 50 serve to rotatably mount the rotor 28.

Upon the opposed inner ends of the bearing members 43 and 50 are arranged ball bearings

53 and 54 respectively for rotatably mounting the compressor cylinder 20 in suitable eccentric relation to the rotor 28.

The lower ball bearing 53 comprises an inner bearing ring 55 fitted on the inner end 56 of the bearing member 43 and supported by a circumferential horizontal shoulder 57 on the bearing member 43 and an outer opposed bearing ring 58 and a row of suitable bearing balls 59 interposed between the two rings. The two rings 55 and 58 are provided with ball runways 60 and 61 respectively and the outer ring 58 is supported by the inner ring 55 through the medium of the row of bearing balls 59.

The outer bearing ring 58 is secured concentrically to the lower cylinder head 24 by means of a ring 62 which is Z-shaped in cross section.

This ring has a vertical peripheral flange 63 within which the lower cylinder head 24 is received and doweled and an inner depending vertical sleeve-like part 64 within which the outer bearing ring 58 is received and an inner circumferential flange 65 opposed to the cylinder head 24 and between which and the cylinder head the outer bearing ring 58 is clamped by the bolts 26 which secure the retaining ring 62 and the lower head 24 upon the lower end of the cylinder.

The arrangement is such that the cylinder is supported vertically in position through the medium of the ball bearing as the lower cylinder head 24 is secured rigidly to the Z-shaped ring and rests upon the upper edge of the outer bearing ring 58. The inner flange 65 of the Z-shaped ring prevents the cylinder rising if there should be any tendency to do so.

The upper ball bearing 54 comprises an inner bearing ring 67, an outer bearing ring 68 and an interposed ring of bearing balls 69. These rings are secured in place similarly to the rings of the lower ball bearing 53, the inner ring being fitted upon the inner end 70 of the upper bearing member 50 and the outer bearing ring being secured upon the top of the upper cylinder head 21 by a Z-shaped securing ring 71. The Z-shaped ring 71 is secured upon the cylinder head 21 by the cylinder head bolts 23.

The upper bearing member 50 is secured to and held in place by a horizontal supporting plate 72 which in turn is held concentrically in position by a concentric bore 73 of the casing within which the plate 72 fits, the bearing member fitting within a central shallow depression 74 in the under side of the plate 72 by bolts 75.

As stated before the motor B surrounds the compressor A and as shown, the motor B comprises a laminated inner rotor member 76 within which the cylinder 20 is concentrically arranged and upon which the rotor 76 is rigidly secured, and an outer laminated, concentrically arranged stator 77. The casing is provided with a concentric bore 78 in which the stator 77 is received and is held, in concentric relation with the rotor 76 but rotatably free therefrom as indicated by the airgap 79. Field coils 80 are carried by the stator.

The stator rests upon an inner circumferential horizontal shoulder 81 on the outer wall of the casing and is held firmly down on same by a metal ring 82 which fits within the lower part of the bore 3 above the bore 78 and which is of slightly larger diameter for convenience in assembly. The ring 82 fits tightly in the bore 82 and when pushed down upon the stator is frictionally held in position. The ring 82 is wide enough to rise high enough to receive and

support the plate 72 to which the upper bearing member is secured. The plate 72 is doweled to the ring 82 and is secured thereto by bolts 83.

The upper bearing 50 being thus positioned vertically through the medium of the stator 77, the ring 82 and the plate 72 a slight clearance is provided at the upper edge of the inner ball bearing ring 67 of the upper ball bearing 54 as shown at 84 to eliminate any possibility of the compressor being bound vertically.

The compressor is, as has been explained, freely rotatable upon the lower ball bearing 53 and the horizontal shoulder 55 on the lower bearing member 43.

The lower cylinder head 24 is provided with a central concentric opening 85 which receives a flange 86 formed on the upper end of the bearing sleeve 45, said flange being eccentric of said sleeve equal to the eccentricity of the rotor 28 and cylinder 20 and the sleeve 45 is held against rotation by any suitable means.

Slight clearance is provided between the upper surface of the flange 86 and the opposed surface of the rotor 28 to avoid any possibility of friction at this point.

The upper cylinder head 24 is provided with a central concentric opening 87 just large enough to clear the compressor shaft 31 which is of course eccentric to the cylinder and said opening 87.

Operating electric current is supplied to the motor by connections 88 which enter through the wall of the casing, through insulation tubes and the connections are sealed to prevent the passage of fluids either into or out of the casing past the connections. It is not thought necessary to illustrate such connections more than to indicate them as shown on Fig. 2. Although an A. C. type of motor is shown, it goes without saying that the invention is not thus limited but that any suitable type of motor can be used within the scope of the appended claims.

The cylinder 20 is driven by the motor B and the compressor rotor 28 is driven by the cylinder 20. For this purpose, as best shown in Fig. 11, a radial vane 89 is provided fixed in the wall of the cylinder 20 and projecting inwardly. This vane is long enough to project across the crescent shaped operating space 34 and into the rotor 28. The vane is fixed in a radial slot provided in the wall of the cylinder by any suitable means such as a pin or key 91. Fig. 11.

There is a slight relative rotational movement between the cylinder 20 and the rotor 28 due to the eccentric relation of these two parts and there is provided a simple means for preventing leakage past the vane 89 at its inner edge and the rotor.

This means comprises a cylindrical plug 92 fitting in a longitudinal bore 93 arranged near the outer cylindrical surface of the rotor 28 and opening at its outer side into the crescent shaped space 34. The plug 92 is provided with a radial slot 94 in which the inner edge portion of the vane 89 fits and can move radially in and out as the compressor is rotated. This construction provides a flexible driving connection between the cylinder 20 and the rotor 28 and which can readily be made pressure tight in operation.

The cylinder and rotor rotate in the direction of the arrow 95 on Fig. 11. A discharge opening 96 is provided in the lower cylinder head 24 and this opening is at the forward side of the vane 89. The gas to be compressed by the opera-

tion of the compressor is delivered to the crescent shaped space 34 through a substantially radial passage 97 in the rotor 28 which connects with a radial passage 98 in the compressor shaft 31, which in turn connects with a longitudinal passage 99 extended down from the radial passage through the lower end of the shaft. In order not to make the radial passage 99 in the shaft too large this radial passage in the shaft and the rotor may be duplicated, as best shown in Fig. 4.

As shown in Fig. 1, the lower bearing member 43 extends down into a central pocket 100 in the base and the lower end of the shaft 31 projects down into this pocket, the lower end of the shaft being chambered as shown at 101 and the passage 99 enters the chamber 101 at its top. The pocket 100, in the base, is connected by a radial horizontal passage 102 through the metal of the base to a threaded opening 103 to which a supply pipe can be connected when the compressor is used for compressing gases other than free air. The pocket 100 is sealed against the entrance of oil from the lower part of the casing by the base 41 of the bearing member 43.

Through the entrance passages 97 entering the compressor behind the vane 89, the gases fill the space as the cylinder rotates and are compressed and forced out through the discharge opening 96. The discharge opening 96 is controlled by a valve 104. The lower cylinder head 24 is provided with a shallow recess 105 to contain the valve 104 which as shown comprises a flat strip of spring metal extending over the opening 96, see Fig. 14, and a second strip 106 of similar metal and the strips clamped to the head 24 by screws 107. The strip 106 is rounded up between its ends so that its free end is yieldingly pressed against the free end of the strip 104. This construction provides a very efficient check valve which effectively prevents the return to the cylinder of any of the expelled gases. The compressed gases are discharged into the casing C and accumulate in the casing. To permit the escape of the compressed gases from the casing the plate 72 is provided with many openings 108 which permit the gases to escape freely into the space 109 above the plate and beneath the cover 31. At one point the cover 31 is provided with an opening 110 through which the compressed gasses can be discharged for use through any suitable pressure controlling valve which may be adjusted to permit the discharge of the compressed gases at the desired pressure.

Another feature of the invention relates to automobile means of supplying ample lubrication to all of the bearings of the compressor for reducing friction and to all of the opposed movable surfaces to seal such spaces and increase the efficiency of the compressor.

The lower part of the casing provides a storage space for a supply of oil as shown at 111 and I provide means operated continuously, while the compressor is operating, for lifting oil from this supply and forcing it to the various points where it is required for lubrication and sealing purposes.

For lifting and forcing the oil I provide an auxiliary pump which comprises an inner extension 112 at one end of the vane 89, best shown in Fig. 4, which is the operating vane of the auxiliary pump. This auxiliary vane extends radially inward into a crescent shaped space 113 formed at the upper end of the rotor 28.

The rotor as shown is provided with a con-

centric recess 114 (Figs. 4 and 10) and the upper cylinder head 21 is provided with an inwardly extending rib 115. The rib 115 is concentric with the cylinder and the recess 114 is concentric with the rotor and they are so proportioned that the outer surface of the rib 115 is tangential to and in contact with the opposed surface of the recess 114 at one point as shown at 116 Fig. 10 thus forming the crescent shaped space 113 through which the auxiliary vane 112 sweeps as the compressor is rotated.

To feed the oil from the supply 111 to this space I provide a passage 118 which extends longitudinally up through the shaft 31 from a point near its lower end to the height of the auxiliary pump where it is connected to the auxiliary pump space 113 by an upwardly inclined passage 119 extending out through the shaft 31 and the adjacent part of the rotor 28 and ending just beyond the inner wall of said space 113. The lower end of the longitudinal passage 118 connects with a substantially radial feed passage 120 which connects it with a circumferential groove 121 formed in the outer surface of the shaft 31.

The oil is fed to this groove 121 and passage 120 from the base of the casing through a passage 122 in the lower bearing member 43 and the bearing sleeve 45 and the inner end of which registers with the groove 121. A feed tube 123 connects the feed passage 122 with an oil strainer 124 submerged in the oil body 111. The oil strainer 124 comprises a tubular ring 124' and to which the feed tube 123 is connected. The ring 124' is provided with many small inlet openings 125 on its inner side and the ring is covered with a fine wire mesh strainer 16 to prevent any foreign particles entering the oiling system.

The delivery of the oil from the auxiliary pump space 113 is mainly through a small opening 127 extending through the inner wall of the pump space and adapted to deliver the oil into the space 87 within the rib 115.

The oil is thus delivered into contact with the shaft 31 in the space 87.

The oil also is delivered from the auxiliary pump out between the adjacent end of the rotor and the inner surface of the upper head thus assisting in sealing the compressor space at this point. The oil is further delivered along the surfaces of the parts which form the flexible connection between the cylinder 20 and the rotor 28.

The bearing member 50 has an upward extension 128, the cover 37 being provided with a hollow dome 129 into which the bearing extends. This construction admits of the maximum length of bearing without increasing the height of the compressor. The bearing member 50 is provided with a bearing sleeve 130 of suitable bearing metal within which the shaft 31 is received and rotates. The inner surface of the sleeve is provided with a spiral oil groove 131 which opens at its lower end into the space 87 and is open at its upper end to permit the oil to escape into the interior of the pump casing. The oil is thus fed through the whole length of the bearing and the oil that escapes from the upper end of the oil groove 131 flows down around the upper projection 128. The plate 72 is provided with a central opening 132 which forms a pocket 133 surrounding the base of the projection 128 to receive the excess oil and said pocket is provided with a drain hole 134 extending down through the bearing member 50 and directing the excess oil back into the interior of the casing.

The top surface of the top cylinder head 21

is provided with a shallow recess 135 which extends from the center opening 87 and is large enough in diameter to extend out to the ball bearings 54. The oil is thus delivered to the ball bearing 54 and any surplus oil works through the ball bearings out into the casing.

To direct oil to the lower end of the rotor 28 and to the lower bearing the shaft 31 is provided in its outer surface with a longitudinally extending oil groove 136, the upper end of which extends into the oil space 87 and the lower end of which extends slightly below the lower end of the rotor 28.

For delivering oil to the lower end of the rotor 15 to lubricate the opposed flat surfaces of the rotor 28 and the lower head 24, an inclined oil feed passage 137 (Fig. 11) is provided extending through the body of the rotor the upper end of which connects with the groove 136 and its 20 lower end connects with a substantially concentric groove 138 formed in the lower flat end 30 of the rotor. Preferably the groove 138 is not a complete circular groove and the oil is delivered to the groove near one end of the groove and, the other end being closed, the pressure under which the oil is delivered causes it to fill the groove and be forced out radially between the opposed flat surfaces of the rotor and the lower head thus not only effectively lubricating these 25 parts but also effectively sealing this point against the escape of the bases being compressed.

The lower end 139 of the oil feed groove 136 extends slightly below the lower flat end 30 of the rotor and within the upper end of the bearing sleeve 45. As best shown in Figs. 15 to 17 this sleeve is provided at its upper end with segmental cut away portions forming, in conjunction with the shaft 31, segmental pockets 140 and 141 with which the oil feed passage 136 successively communicates once for each revolution of the shaft.

The pocket 140 is connected to an oil feed passage 142 which extends out through the sleeve flange 86 and delivers oil within the recess 85 between the edge of the flange and the adjacent 45 surface of the lower cylinder head 24. The excess oil works down between these surfaces to the lower side of the cylinder head which, similar to the upper head, is provided with a shallow recess 143 which extends from the inner recess 50 85 out to the ball bearing 53, the excess oil escaping through the ball bearing to collect in the bottom of the casing.

The pocket 141 connects with the upper end of a spiral oil feed groove 144 formed on the inner 55 surface of the bearing sleeve 45. The lower end of the groove 144 connects with a substantially radial oil passage 145 formed in the body of the lower bearing member 43 and the outer end of which connects with a delivery tube 146 which delivers the excess oil into the base of the casing.

The compressed gases which are forced past the check valve 104 escape freely through the ball bearing 53 into the interior of the casing and as has been explained through the openings 108 in the top plate 72 into the space 109 and from this space through the delivery opening 110.

As the oil is discharged, as has been explained, at several points, from the compressor there will naturally be more or less particles of oil floating in the gases within the casing and I preferably provide a large number of the openings 108 through the top plate 72 mainly to reduce the speed of the gases through these openings and I provide a fine wire gauze filter 147 secured on the under side of the plate 72 and covering said

openings to assist in filtering out the oil carried by the gases.

The large area of escape thus provided prevents any clogging thereof to prevent the free escape of the gases and so reduces the rate of flow that the oil clings to the screen and drops back into the casing. Furthermore the many holes 108 serve to appreciably reduce the weight of the plate 72.

From the drawings and the foregoing description it will now be clear that by means of this invention I am enabled to provide a compressor of minimum height, commensurate with the capacity thereof, and one which can be operated efficiently practically continuously.

As many modifications of the invention will obviously suggest themselves to one skilled in the art I do not limit or confine the invention to the specific details of construction except within the scope of the appended claims.

Throughout the specification and the appended claims, the term "positive displacement pump" is used in the sense that it defines a pump which is capable of building up a relatively high head pressure, such for example as a gear pump, a reciprocating pump, a rotatory pump with one or more vanes or blades, and the like—as distinguished from a viscosity pump such as shown in Lieb 1,963,024.

I claim:

1. In a compressor, an air-tight dome, pump members within the dome including a rotatable hollow cylindrical member, a core member mounted therein in eccentric tangential relation for rotation about its own center, and end plates rigidly secured to one of said members and having infinitesimally small end clearances with the other to form a pump chamber, means dividing the chamber into intake and discharge sections comprising a blade rigidly secured to the same member to which the end plates are secured and having a sealed fit with said member and said end plates, said blade having a sliding and rocking engagement with the other member, means for driving the blade through one of the elements rigid therewith to produce a pumping action, bearing supports for the pump members, and for at least one of said pump members on both sides thereof at points farther apart than the width of the pumping chamber, a lubricating and gas sealing system associated with the compressor including means adapted to deliver oil to said infinitesimal end clearances in sufficient quantity and at a pressure at least in excess of dome pressure to effectively seal said clearances against gas leakage, said cylindrical member being driven by a rotary motor surrounding the cylindrical member and substantially centered in the center plane of the cylindrical member, the rotor of the motor being carried by the cylindrical member and supported by its bearings.

2. In a compressor, an air-tight dome, pump members within the dome including a rotatable hollow cylindrical member, a core member

mounted therein in eccentric tangential relation for rotation about its own center, and end plates rigidly secured to one of said members and having infinitesimally small end clearances with the other to form a pump chamber, means dividing the chamber into intake and discharge sections comprising a blade rigidly secured to the same member to which the end plates are secured and having a sealed fit with said member and said end plates, said blade having a sliding and rocking engagement with the other member, means for driving the blade through one of the elements rigid therewith to produce a pumping action, bearing supports for the pump members, and for at least one of said pump members on both sides thereof at points farther apart than the width of the pumping chamber, a lubricating and gas sealing system associated with the compressor including means adapted to deliver oil to said infinitesimal end clearances in sufficient quantity and at a pressure at least in excess of dome pressure to effectively seal said clearances against gas leakage, said cylindrical member being driven by a rotary motor surrounding the cylindrical member and substantially centered in the center plane of the cylindrical member, the rotor of the motor being carried by the cylindrical member and supported by its bearings, said bearings being of a rolling type.

3. In a compressor, a gas-tight dome, pump members therein including a rotatable hollow cylinder and a rotatable core mounted in eccentric tangential relation thereto, each being rotatable about its own center, end plates closing the space between the members to form a pump chamber, a blade dividing the chamber into intake and discharge sections, the end plates and blade being rigidly secured to one of the members, the end plates having infinitesimal clearances with the other member, and the blade sliding in a rocker in said other member and having at least a portion extending at all times at least to the pivotal axis of the rocker, means for driving the rigid assembly including the end plates and blade and through the blade driving said other member, bearings for one of said members on both sides thereof and bearing means for the other member restraining it from canting, and means for sealing and lubricating said infinitesimal clearances including a secondary pump within the dome and including a secondary cylinder and a secondary core formed between the main core and an end plate adjacent thereto, with the cylinder formed as a recess in one of said last-named members, and the secondary core formed as a boss integral with the other of said last-named members, said secondary pump being constructed and arranged to deliver oil to said infinitesimal clearances in sufficient quantity and at a pressure at least in excess of the pump chamber pressure to effectively seal said clearances against gas leakage.

WM. WARD DAVIDSON.
